[57] **CLAIM**

The ornamental design for a handle for fishing rods, as shown and described.

DESCRIPTION

FIG. 1 is a perspective view of a handle for fishing rods, showing my new design;

FIG. 2 is a perspective view thereof;

FIG. 3 is a left side elevational view thereof;

FIG. 4 is a right side elevational view thereof;

FIG. 5 is a top plan view thereof;

FIG. 6 is a front elevational view, the rear being a mirror image thereof; and,

FIG. 7 is a bottom plan view thereof.

The broken line showing of a rod and reel in FIG. 1 is for illustrative purposes only and forms no part of the claimed design.

FIG. 1

FIG. 2

FIG. 5

FIG. 3

FIG. 4

FIG. 6

FIG. 7
